UNITED STATES PATENT OFFICE.

CHARLES H. GOODYEAR, OF CEDAR RAPIDS, IOWA.

LOOSE-LEAF NOTE-BOOK.

No. 912,111.

Specification of Letters Patent.

Patented Feb. 9, 1909.

Application filed May 11, 1908. Serial No. 432,326.

To all whom it may concern:

Be it known that I, CHARLES H. GOOD-
YEAR, a citizen of the United States, residing
at Cedar Rapids, in the county of Linn and
5 State of Iowa, have invented certain new
and useful Improvements in Loose-Leaf
Note-Books; and I do hereby declare the fol-
lowing to be a full, clear, and exact descrip-
tion of the invention, such as will enable
10 others skilled in the art to which it appertains
to make and use the same.

The object of this invention is to provide a
note book, for stenographers, students and
others, having detachable leaves and a binder
15 in such form as to be conveniently held in
the hand or on the lap, and adapted to hold
securely the leaves as detached from their
original position in the book.

The nature of the invention is fully dis-
20 closed in the description and claim following,
reference being had to the accompanying
drawing, which shows my improved note
book open as in use.

In the drawing the binder or portfolio is
25 shown made up of four principal sections,
comprising a stiff back A, two covers, B and
C hinged to the back, the latter cover being
somewhat wider than the other, and having
hinged to it a flap D. The wider cover is
30 provided near its outer margin with studs E
terminating in balls E¹, which engage sockets
F in the flap. The fastener is similar to the
familiar glove fastener, and requires no par-
ticular description, as I make no claim to it
35 specifically. The studs are used, however,
in my binder to hold the separate written
leaves as detached from the original packet
G in the adjacent part of the binder. In
practice these leaves are made to be folded
40 when the book is closed, but open out flat
when it is opened, making a convenient tab-
let, with folio leaves, on which to take notes.
The leaves are held in the binder by a cord
(preferably elastic) H passing through eye-
45 lets I in the back. The leaves are notched
at J to engage this cord at each end, and by
this means are held centrally at all times.

In practice they are also perforated along the
middle, as shown at K, so as to be easily torn
into halves, and when so separated they are 50
easily mounted on the studs E, being
punched at L for this purpose. When the
flap D is closed the detached leaves are of
course locked in position. The flap, if made
wide enough, overlaps the cover B, when 55
closed, and locks it in that position.

In the use of the book the operator is sup-
posed to insert a comparatively small packet
of leaves under the retaining cord, which is
done in a moment. He now writes on the 60
uppermost sheet as the book lies open, turn-
ing the right hand leaf to write on the back
side (so as to correspond with the left hand
leaf) or not, as he prefers. When both pages
are filled he tears the double sheet apart 65
along the binding cord, which may also be
done in an instant. If too busily engaged to
file them then, he simply lays them down,
and files them later, as already described.
In taking notes he has a comparatively thin, 70
stiff-backed tablet, which may be held in the
hand or on the knee, when occasion requires,
instead of a bulky tablet, or what is even
more inconvenient, a book of the ordinary
construction. And when he comes to tran- 75
scribe his notes he has a series of separate
leaves in condition to be conveniently
mounted alongside the typewriter, and laid
aside, leaf by leaf, as fast as transcribed.

Having thus described my invention, I 80
claim:

In a loose-leaf note-book, the combination
with detachable leaves, perforated for en-
gagement with a file, of a binder adapted to
hold said leaves, and having one extended 85
side provided with studs to engage said holes
and a flap to close over said studs and hold
the filed sheets, substantially as specified.

In testimony whereof I affix my signature
in presence of two witnesses.

CHARLES H. GOODYEAR.
